US0D1112679S

(12) **United States Design Patent** (10) **Patent No.:** **US D1,112,679 S**
(45) **Date of Patent:** **** Feb. 10, 2026**

(54) **PERFUME VAPORIZER**

(71) Applicant: **Lefen Industrial (Shen Zhen) Co., Ltd.**, Shenzhen (CN)

(72) Inventor: **Daikuan Zhong**, Shenzhen (CN)

(73) Assignee: **Lefen Industrial (Shen Zhen) Co., Ltd.**, Shenzhen (CN)

(**) Term: **15 Years**

(21) Appl. No.: **29/926,042**

(22) Filed: **Jan. 29, 2024**

(30) **Foreign Application Priority Data**

Jan. 18, 2024 (CN) 202430035034.9

(51) **LOC (15) Cl.** **23-04**

(52) **U.S. Cl.**

USPC **D23/361**

(57) **CLAIM**

The ornamental design for a perfume vaporizer as shown and described.

DESCRIPTION

FIG. 1 is a perspective view of a perfume vaporizer showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the perfume vaporizer that form no part of the claimed design.

1 Claim, 8 Drawing Sheets
